Delmar D. Rhoads, Fort Wayne, Ind.

Application December 20, 1957, Serial No. 48,979

Term of patent 14 years

(Cl. D14—3)

Figure 1 is a perspective view of a cart showing my new design. The opposite side and rear of the cart are substantially of the same appearance as the respective end and front shown.

Figure 2 is a view of the side opposite that shown in Figure 1 with the door in open position and slid partially back along the side.

Figure 3 is a sectional view of the handle portion taken on line 3—3 of Figure 2.

I claim:

The ornamental design for a cart, as shown and described.
